SAMUEL F. FENN, OF MIDDLETOWN, CONNECTICUT, ASSIGNOR TO HIMSELF AND F. B. CLARK, OF THE SAME PLACE.

Letters Patent No. 71,727, dated December 3, 1867.

IMPROVEMENT IN BIT BRACES.

The Schedule referred to in these Letters Patent and making part of the same.

TO ALL WHOM IT MAY CONCERN:

Be it known that I, S. F. FENN, of Middletown, in the county of Middlesex, and State of Connecticut, have invented a new and useful Improvement in Bit-Brace; and I do hereby declare that the following is a full, clear, and exact description thereof, which will enable those skilled in the art to make and use the same, reference being had to the accompanying drawings, forming part of this specification, in which—

Figure 1 represents a side view of my improved bit-holder, attached to the end of a brace.

Figure 2 represents a view of the same on another side.

Figure 3 is a section taken in the line $x x$, fig. 1.

Figure 4 is an end view.

Similar letters of reference indicate corresponding parts.

This invention relates to an improvement in a bit-brace for holding the bit in its place in the end of the spindle after a hole has been bored, and when the bit is withdrawn therefrom.

The common method of securing the bit in the brace is by means of a set-screw, which catches in a notch in the shank of a bit. My improvement dispenses with the set-screw, and consists in attaching a spring-stirrup by a pivot to the round end of the spindle, which shall turn aside to allow the bit to be introduced as usual into the brace, and is then placed so as to catch over the round part of the bit against the shoulders, formed by the square shank, and thus hold the bit in place, as hereinafter more particularly described.

A represents a round spindle of a brace, or the ends of a boring-stock, which is provided with a square hole or deep recess in the point; for the reception of a boring-bit, as usual. Back of the base of the hole, in the end of the brace, a stationary pin, b , is run through the centre, having ends projecting from the sides. A stirrup, a , is hung on the pivot b , formed of thin steel plates, the ends of which are curved on the inner sides, to fit the outside of the spindle, in such manner that they shall lie close and bear against the sides of the spindle by their spring pressure, when the stirrup is placed in line therewith, for holding a bit in its place in the hole, and may be turned on the pivot b , so as to spread without coming off, when the stirrup is turned, to put a bit in the brace or take it therefrom. The lower end or foot of the stirrup a is formed with a slot in it, which slips over the round part of the bit, and catches against the square shoulder thereof, to clamp and hold it in the spindle, and prevent it from coming out, when the bit is withdrawn from a hole that has been bored, as shown clearly in the drawings.

Having thus described my invention, what I claim as new, and desire to secure by Letters Patent, is—

The spring-stirrup a , attached by the pivot b to the spindle A of a brace, constructed and operating substantially as and for the purpose described.

SAMUEL F. FENN.
